UNITED STATES PATENT OFFICE.

HUGO PICK, OF CHICAGO, ILLINOIS.

DESIGN FOR A TUMBLER.

47,800.

Specification for Design.

Patented Sept. 7, 1915.

Application filed June 7, 1915. Serial No. 32,747. Term of patent 14 years.

To all whom it may concern:

Be it known that I, Hugo Pick, a citizen of the United States, residing at Chicago, in the county of Cook and State of Illinois, have invented a new, original, and ornamental Design for Tumblers, of which the following is a specification, reference being had to the accompanying drawing, forming a part thereof.

In the drawings: Figure 1 is a side elevation of a tumbler embodying the invention and Fig. 2 is a plan.

The tumbler, embodying the invention, is

characterized in having a slightly upwardly flaring side *a* extending to a point *b* and a slightly inwardly tapered side *c* extending from the point *b* to the upper rim of the glass.

I claim:

The new and ornamental design for a tumbler, as shown and described.

HUGO PICK.
